(57) **CLAIM**

The ornamental design for a user manipulation massaging device, as shown and described.

DESCRIPTION

FIG. 1 is a top view of a user manipulation tension reliever showing my new design with faceted sides and changing contact elements;

FIG. 2 is a back elevational view thereof;

FIG. 3 is a left side elevational view thereof;

FIG. 4 is a front elevational view thereof;

FIG. 5 is a right side elevational view thereof;

FIG. 6 is a bottom elevational view thereof; and,

FIG. 7 is an isometric view thereof.
